UNITED STATES PATENT OFFICE.

JOHN E. BUCKLEY, OF NEWARK, NEW JERSEY, ASSIGNOR OF ONE-HALF TO FRANK BRABSON, OF NEWARK, NEW JERSEY.

DESIGN FOR A TARGET.

53,881.

Specification for Design.

Patented Oct. 7, 1919.

Application filed May 10, 1917. Serial No. 167,844. Term of patent 3½ years.

To all whom it may concern:

Be it known that I, JOHN E. BUCKLEY, a citizen of the United States, residing in Newark, in the county of Essex and State of New Jersey, have invented a new, original, and ornamental Design for Targets, of which the following is a specification, reference being had to the accompanying drawing, forming part thereof.

Figure 1 is a front view of a target embodying my invention;

Fig. 2 is an edge view of the same, and Fig. 3 is a rear view of the target.

I claim:

The ornamental design for a target as shown.

JOHN E. BUCKLEY.
